(57) **CLAIM**

The ornamental design for a display container for disposable capsules for the preparation of beverages, as shown and described.

DESCRIPTION

FIG. 1 is a front perspective view of a display container for a disposable capsule for the preparation of a beverage with a supporting element in a closed configuration, according to the invention;

FIG. 2 is a front perspective view thereof, with the supporting element in an open configuration;

FIG. 3 is a front view thereof;

FIG. 4 is a right side view thereof;

FIG. 5 is a rear view thereof;

FIG. 6 is a top view thereof;

FIG. 7 is a bottom view thereof;

FIG. 8 is a front perspective view of a second embodiment of a display container for a disposable capsule for the preparation of a beverage with a supporting element in a closed configuration, according to the invention;

FIG. 9 is a front perspective view thereof, with the supporting element in an open configuration;

FIG. 10 is a front view thereof;

FIG. 11 is a right side view thereof;

FIG. 12 is a rear view thereof;

FIG. 13 is a top view thereof;

FIG. 14 is a bottom view thereof;

FIG. 15 is a front perspective view of a third embodiment of a display container for a disposable capsule for the preparation of a beverage with a supporting element in a closed configuration, according to the invention;

FIG. 16 is a front perspective view thereof, with the supporting element in an open configuration;

FIG. 17 is a front view thereof;

FIG. 18 is a right side view thereof;

FIG. 19 is a rear view thereof;

FIG. 20 is a top view thereof;

FIG. 21 is a bottom view thereof;

FIG. 22 is a front perspective view of a fourth embodiment of a display container for a disposable capsule for the preparation of a beverage with a supporting element in a closed configuration, according to the invention;

FIG. 23 is a front perspective view thereof, with the supporting element in an open configuration;

FIG. 24 is a front view thereof;

FIG. 25 is a right side view thereof;

FIG. 26 is a rear view thereof;

(Continued)

FIG. 27 is a top view thereof; and,
 FIG. 28 is a bottom view thereof.
 The broken lines in the drawings depict portions of the
 display container that form no part of the claimed design.
